CLAIM

I claim the ornamental design for a foot spa, as shown and described.

DESCRIPTION

FIG. 1 is a top front perspective view of the foot spa of the present invention.

FIG. 2 is a top rear perspective view of the foot spa of FIG. 1.

FIG. 3 is a front elevation view of the foot spa of FIG. 1.

FIG. 4 is a rear elevation view of the foot spa of FIG. 1.

FIG. 5 is a side elevation view of the right side of the foot spa of FIG. 1.

FIG. 6 is a side elevation view of the left side of the foot spa of FIG. 1.

FIG. 7 is a top plan view of the foot spa of FIG. 1; and,

FIG. 8 is a bottom plan view of the foot spa of FIG. 1.

In the drawings, the broken lines depict portions of the foot spa that form no part of the claimed design.
